UNITED STATES PATENT OFFICE

170,737

COMBINED FOOD AND BEVERAGE VENDING STATION

Louis A. Zon, Buffalo, N. Y.

Application February 10, 1953, Serial No. 23,527

Term of patent 14 years

(Cl. D13—1)

To all whom it may concern:

Be it known that I, Louis A. Zon, a citizen of the United States of America and residing at Buffalo, in the county of Erie and State of New York, have invented a new, original, and ornamental Design for a Combined Food and Beverage Vending Station, of which the following is a specification, reference being had to the accompanying drawings forming part thereof.

Fig. 1 is a perspective view of a combined food and beverage vending station embodying my new design, this view being taken from a point in front of and slightly above and to one side of the station.

Fig. 2 is a top plan view thereof.

Fig. 3 is an elevational view of the front thereof, viewed from the right of the station as shown in Fig. 2, the rear side being similar in appearance.

Fig. 4 is a side elevational view thereof, viewed from the lower side of the station as shown in Fig. 2, the opposite side being similar in appearance.

I claim:

The ornamental design for a combined food and beverage vending station, substantially as shown.

LOUIS A. ZON.
